BALL CATCHING AND THROWING DEVICE

Filed Jan. 26, 1929

Inventor:

Karl Robert Uhlig

UNITED STATES PATENT OFFICE

KARL ROBERT UHLIG, OF SPIEGELAU, GERMANY

BALL-CATCHING AND THROWING DEVICE

Application filed January 26, 1929, Serial No. 335,226, and in Germany January 27, 1928.

This invention relates to a device for catching and throwing balls and consists in the provision of a casing containing a hollow, spring-pressed plunger wherein a spring-controlled rod carrying a ball-catching shell is arranged to slide, the plunger being retained in depressed position in opposition to its spring, by latches which tend to release it and which are normally prevented from so doing by a wedge connected to the rod, said wedge being adapted, on the depression of the rod by the impact of a ball on the shell, to release the latches so as to enable the plunger to throw the ball.

Fig. 1 of the accompanying drawings represents a longitudinal sectional view of the preferred form of the device showing the plunger in extended position,

Fig. 2, another sectional view of the device showing the plunger depressed for use, and Fig. 3, a part elevation of the device.

The device comprises a cylindrical casing 1 which is secured at one end, by means of a screw-bolt 3 to a hollow stem 2, the other end of the casing being closed by a screw-cap 22 which is formed with a centrally disposed, open sleeve 20. The casing serves as a guide for the head 9 of a hollow plunger the stem 8 of which is guided in the sleeve 20. A solid core 12 fitted in the head 9, is provided with an axial bore 11 and with a diametral bore 10. In each end portion of the diametral bore a latch is mounted which comprises a bolt 15, a spring 16 and a guide disc 13, the latter being mounted on the bolt. Another disc 17, which is screwed into the outer end of the bore, guides the end of the bolt which passes through an aperture in the head 9 for engagement with an aperture 31 in the casing 1. The spring 16, which bears against the two discs 13 and 17, tends to release the bolt from the casing.

A rod 25 is arranged to slide in the plunger stem 8 and is guided in the bore 11 of the core 12 and in the outer end 8a of said stem. A pear-shaped wedge 28 which extends from the inner end of the rod 25, serves as an abutment for the inner ends 14 of the latch bolts 15. A spring 23, which surrounds the rod 25, bears against a collar 24 on the latter and

against the core 12 and tends to hold the wedge 28 in a position in which it maintains the latch bolts in engagement with the apertures 31. On the rod being depressed in opposition to the spring 23, the narrow portion 27 of the wedge takes the thrust of the latches and allows them to be retracted so as to release the plunger. The outer, projecting end 26 of the rod 25 carries a concave shell 29 which serves as a ball catcher and thrower. The throwing is effected by means of the plunger which for this purpose is controlled by a spring 19 which surrounds the stem 2 and a tube 18 which latter is connected by means of a flange to the core 12 and is adapted to telescope within the stem 2. An operating handle 4 is secured to the stem 2 by means of a tang 5 and a screw-bolt 7 and carries a hand-protecting shield 6. A headed screw 33, secured to the head 9 of the plunger, engages in a longitudinal slot 32 in the casing 1 and prevents rotary displacement between the plunger and the casing. A soft insertion 21 in the screw-cap 22 serves as a buffer for deadening the shocks of the plunger head.

The plunger is depressed for operation by placing the shell 29 against the ground and pushing the casing downwards on the stem 8 as far as possible, the latch bolts 15 being then in alignment with the apertures 31. As soon as the pressure in the casing is relieved, the rod 25 moves forwards and displaces the wedge 28 between the latches so as to force the latter into engagement with the apertures 31, thereby locking the plunger in depressed position, as shown in Fig. 2. If now the device is operated so as to catch a ball in the shell 29, the impact of the ball on the latter will cause the rod 25 to be depressed so as to release the latches and the plunger, whereupon the latter will react on the shell so as to throw the ball.

I claim:

1. A ball-catching and throwing device comprising a casing, a spring-pressed, hollow plunger fitted in said casing, a spring-controlled rod arranged to slide in said plunger, a ball-catching shell carried on the outer end of the rod, latches adapted to re-

tain the plunger in depressed position in the casing in opposition to its spring, springs tending to release the latches, and a wedge on the rod adapted to retain the latches normally in operative position and to release them and the plunger on being depressed by the impact of a ball on the shell.

2. A device as claimed in claim 1 wherein the latches consist of bolts mounted radially in the plunger and are adapted to engage in apertures in the casing, and wherein the wedge is round and pear-shaped.
